FIRE EXTINGUISHER

Edwin P. Van Sciver, Philadelphia, Pa., assignor
to Pyrene Manufacturing Company, Newark,
N.J., a corporation of Delaware

Application May 31, 1951, Serial No. 15,349

Term of patent 14 years

(Cl. D16—2)

To all whom it may concern:

Be it known that I, Edwin P. Van Sciver, a citizen of the United States, residing at Philadelphia, in the county of Philadelphia and State of Pennsylvania, have invented a new, original, and ornamental Design for Fire Extinguisher, of which the following is a specification, reference being had to the accompanying drawing, forming part thereof.

Fig. 1 is a front elevational view of a fire extinguisher embodying my new design;

Fig. 2 is a side elevation thereof; and

Fig. 3 is a top plan view.

I claim:

The ornamental design for a fire extinguisher, substantially as shown.

EDWIN P. VAN SCIVER.
